SPLITTING MACHINE

Orlie A. Hawkins, Lamar, Colo.

Application August 1, 1935, Serial No. 34,291

10 Claims. (Cl. 146—73)

My invention relates generally to apparatus for splitting and longitudinally dividing objects of relatively small cross section, and particularly to a device for accurately and cleanly longitudinally splitting yucca blades, reeds, and the like, and an important object of the invention is to provide apparatus of the character described which is relatively simple and inexpensive yet extraordinarily efficient.

Another important object of my invention is to provide apparatus of the character indicated above which is capable of quantity production at a relatively low cost for power and labor.

Another important object of my invention is to provide in apparatus of the character indicated above means for accurately and uniformly feeding the yucca blades to the cutters and away from the cutters, so that the yucca blades both before and after splitting occupy relatively the same positions and are positively prevented from being unduly twisted or otherwise displaced and mutilated.

Another important object of my invention is to provide in apparatus of the character indicated above semi-automatic means for feeding the yucca blades to the cutters.

Another important object of my invention is to provide adjustable means for keeping the cutters clean and for holding the yucca blades accurately in relation to the cutters during the cutting operation.

Another important object of my invention is to provide cutter means which accurately and cleanly split the yucca blades into predetermined sections.

Other important objects of my invention will be apparent from a reading of the following description in connection with the drawings, wherein for purposes of illustration I have shown a preferred embodiment of my invention.

In the drawings:—

Figure 1 is a general top plan view of apparatus in accordance with the invention.

Figure 2 is a side elevational view thereof looking upwardly in Figure 1.

Figure 3 is an elevational view of a portion of the opposite side.

Figure 4 is a longitudinal vertical sectional view taken through Figure 1 approximately on the line 4—4.

Figure 5 is a horizontal sectional view through the adjustable guide assembly.

Figure 6 is a longitudinal sectional view taken through one end of the cutter assembly.

Figure 7 is an elevational view showing the

operative connections between the feeding rollers.

Figure 8 is a top plan view of the oscillating distributor.

Figure 9 is a perspective view of one of the guide fingers.

Figure 10 is a perspective view of one of the guide finger spacers.

Figure 11 is a perspective view of one of the cleaner plates.

Figure 12 is a longitudinal sectional view taken 10 through one of the feeding rollers.

Referring in detail to the drawings, the numeral 5 refers generally to a suitable stand which includes legs 6 and a top 7 including the longitudinal top members 8 and 9.

Intermediate the ends of the side members 8 and 9 rise the vertical brackets 10 and 11 between the upper ends of which is fixed the feeding hopper 12 which includes the vertical wall 13, the angulated bottom 14 and the sides 15 20 and 16.

Duplicates of the sides 15 and 16 which are generally designated 17 are arranged across the bottom 14 to provide chutes for guiding the yucca blades and the like and properly disposing the same upon reception into the hopper. The bottom 14 is cut away as indicated at 18 and in the opening is located the oscillating plate or distributor 19 which is formed with longitudinally spaced rectangular openings 20 corresponding in 30 number to the chutes and disposed in registry therewith as shown in Figure 1. The oscillating plate 19 has journal pins or stub shafts 21 and 22 at its opposite ends as shown in Figure 8 and the lower pin 22 (Figure 1) has fixed thereon 35 the segmental crank 23 which has a crank pin 24 with which is engaged the upper end of a connecting rod 25 whose opposite end is connected eccentrically as indicated at 26 to a disk 27 fixed on the shaft 28 which is journaled in 40 the uprights 10 and 11 and has thereon a pulley 29 operatively connected by a belt 30 to a pulley 31 on the shaft 32 on which is the cutter assembly 33, whereby the plate 19 is caused to angularly oscillate up 45 and down so as to alternately enlarge and reduce the apertures presented for reception of the yucca blades in the chutes in the hopper.

Brackets 34 extending from the uprights 10 and 11 in a left hand direction journal the opposite ends of the upper feeding roller 35 which is a cylinder 36 formed on its surface with projecting small pins 37 which dig into the yucca blades or the like so as to gain a good traction or pull thereon for pulling the blades out of the 55

chutes of the hopper, while the blades are somewhat bent or contorted in a downward direction as they come through the opening 18 and the openings 20 in the oscillating plate 19. A 5 similarly mounted lower feeding roller 38 below and to the right of the roller 35 engages the underside of the yucca blades while the roller 35 engages the upper side thereof in cooperative action. On the end of the shaft 28 opposite the 10 pulley 29 is a small pulley 39 which has a belt 40 trained thereover and also on a pulley 41 on one end of the roller 35, whereby the roller 35 is driven in the proper direction. A reversing belt 42 trained over the pulley 41 and also over 15 a pulley 43 on the lower roller 38 operates the roller 38 in an opposite direction at a slower speed than the roller 35.

Feeding tubes 44, one for each of the chutes, are downwardly angulated as indicated in Figure 4, and have their upper ends directly below and in receiving relation to the feeding rollers 35 and 38 and have their lower ends cut off at an angle close to the cutter assembly 33 for feeding the allocated yucca blades through the 20 cutters corresponding to the individual tubes.

The cutter assembly shaft 32 is journaled in bearings 45 and 46 on the respective side members 8 and 9 of the supporting frame. A pulley 47 at one end of this shaft is arranged for the 25 application of suitable power for driving the machine, while a smaller pulley 31 fixed on the opposite end of this shaft has the already described belt 30 trained thereover for driving the feeding rollers and the oscillating plate above 30 described.

The cutter assembly consists of the shaft 32 which is plain and smooth and has thereon the circular knife cutters 50 which are in circular disk form with sharpened edges 51, the spacers 40 52, the reduced threaded end portion 53 on which is the lock nut 54 which locks the knives and spacers in their selected positions, and the smooth portions 55 on the opposite ends of the shaft which turn in the bearings 45 and 46 and fixedly 45 support the pulleys 31 and 47. The knives 50 are arranged in groups of five with an extra spacer 52 between groups as indicated in Figure 1, the groups corresponding to the tubes 44 so as to be in cutting relation to the yucca blades 50 as they issue from the corresponding tubes. Desired re-arrangements of the groupings of the knives may be readily made by loosening the nuts 54 on the opposite ends or at only one end of the cutter assembly and then re-arranging the 55 spacers 52 and tightening the nuts 54 again. It is obvious that the number of knives in the groups may be changed at will.

A generally similar arrangement of operative elements and spacers is provided for the guide finger assembly which is generally designated 55 and which contains the square shaft 56 with the reduced threaded ends 57 and 58 on which are arranged the clamping nuts 59 and 60. Outward of the threaded portions are smooth portions 61 and 62 which turn in the supports 10 and 11 and outwardly of these smooth portions are further reduced threaded portions 62 and 63 on which are threaded the adjusting levers 64 and 65 which are clamped in place by nuts 70 66 and 67.

The levers are arranged on pivots 68 and 69 which traverse the supports 10 and 11 and are locked in place by nuts 70 and 71. It will be obvious that by swinging the levers 64 and 65 75 up and down the relation of the groups of guide

5 fingers 72 to the lower edges of the corresponding groups of cutter blades can be changed, and that further angular changes may be arranged by loosening the nuts 66 and 67 and turning the shaft relative to the levers. The shaft 56 10 is square in cross section and the elongated fingers 72 have square openings 73 receiving the shaft and the washers 74 have correspondingly squared openings 75 so that the fingers cannot turn on the square shaft and the proper grouping and spacing of the fingers is produced. In the embodiment shown four fingers 72 for each 15 group of five cutter blades is provided, the fingers being located between the blades and within the outer ones of each group. 15

It is obvious that the yucca blades upon issuing from the tubes 44 are pushed downwardly by the clockwise rotating knives and that they are prevented from falling out of relation to the knives by the presence of the extremities of the 20 fingers 72 between the cutting edges of the blades as indicated in Figures 1 and 4 and that the yucca blades are thereby properly positioned and held relative to the knives so as to be accurately 25 and cleanly cut for their full length and delivered in proper position to the receiving tray 75 which is supported between the left hand legs 6 and extends in a left hand direction beyond the support 5 and empties into a receiving hopper 76 which is supported on a bracket 77 connected to the legs 6, so that the split blades fall into the hopper in an orderly manner and stack up therein without requiring re-arrangement, so that the split blades may be easily removed from the hopper in proper position for further manufacturing operations. 30

For keeping the cutting edges of the various 35 groups of blades clean and unencumbered, there is provided a cleaner assembly which is generally 40 designated 78. This assembly includes the uprights 79 and 80 which are mounted on the frame support side members 8 and 9 to the left of the bearings 45 and 46. Each upright has pivoted thereto as indicated at 81 and 82 at the inner side thereof a hand lever 83, 84 through one end 45 of which is mounted the square shaft 85 on which is disposed a number of groups of cleaner plates 86 provided with square holes 87 receiving the square shaft 85. The cleaner plates 86 are aligned with the levers 83 and 84 and when the 50 levers are swung on their pivots the cleaner plates are moved toward or away from the sides of the cutter assembly 33. Square washers similar to those shown in Figure 10 are used to space the cleaner plates 86 on the shaft 85 in groups of 55 four to be aligned with the guide fingers 72. The groups of cleaner plates are arranged to correspond with the described groups of cutter knives and yucca blade feeding tubes 44. By positioning the free ends of the cutter blades as shown in Figure 4, accumulations on the cutting edges of the blades are shorn off and prevented from reducing the cutting efficiency of the 60 blades.

Although I have shown and described herein a 65 preferred embodiment of my invention, it is to be definitely understood that I do not desire to limit the application of the invention thereto, and any change or changes may be made in the materials and in the structure and arrangement 70 of the parts, within the spirit of the invention and the scope of the subjoined claims.

What is claimed is:—

1. A yucca blade splitting machine comprising 75 a chute, a plurality of rotary cutting knives, a

guiding and allocating tube in receiving relation to said chute and in feeding relation to some of said knives, positive feeding rollers interposed between the chute and the tube for forcing the 5 yucca blades into position in the tube and into engagement with the knives, and adjustable guide fingers extending beyond the delivery end of the guide tube and disposed between adjacent ones of the knives for causing the yucca blades to 10 engage the edges of the knives in a predetermined manner.

2. A yucca blade splitting machine comprising a chute, a plurality of rotary cutting knives, a guide and allocating tube in receiving relation 15 to said chute and in feeding relation to some of said knives, positive feeding rollers interposed between the chute and the tube for forcing the yucca blades into position in the tube and into engagement with the knives, and adjustable guide 20 fingers disposed beyond the delivery end of the guide tube and between adjacent ones of the knives for causing the yucca blades to engage the knives in a predetermined manner, and knife cleaning means preventing accumulation of matter 25 on the knives.

3. A yucca blade splitting machine comprising a chute, a plurality of rotary cutting knives, a guide and allocating tube in receiving relation to said chute and in feeding relation to some of 30 said knives, positive feeding rollers interposed between the chute and the tube for forcing the yucca blades into position in the tube and into engagement with the knives, oscillating apertured allocating means located between said 35 rollers and said chute for allocating and feeding the yucca blades in said chute to the corresponding tube and knives.

4. A yucca blade splitting machine comprising a chute, a plurality of rotary cutting knives, a 40 guide and allocating tube in receiving relation to said chute and in feeding relation to some of said knives, positive feeding rollers interposed between the chute and the tube for forcing the yucca blades into position in the tube and into engagement with the knives, said knives comprising a cutter assembly containing a shaft, a plurality of disk knives thereon, a plurality of washers slidable on the shaft and located between the disks, and means longitudinally movable on 50 opposite ends of the shaft for clamping the knives and washers together in selected relation.

5. A machine for longitudinally splitting yucca blades, said machine comprising first means for holding and feeding the yucca blades, conduit 55 means into which the blades are selectively fed from said first means, rotary cutters against the edges of which said blades are adapted to be pressed for longitudinally splitting the blades, and second means located between said first 60 means and said conduit means for admitting only a selected number of the blades from said first means into said conduit means, said second means acting to intermittently admit the blades into said conduit means, and opposed rollers interposed 65 between said second means and said conduit means for forcibly positioning the admitted blades in said conduit means and against the cutting edges of the rotary cutters.

6. A machine for longitudinally splitting yucca 70 blades, said machine comprising first means for holding and feeding the yucca blades, conduit means into which the blades are selectively fed from said first means, rotary cutters adjacent the conduit means for longitudinally splitting the 75 blades as they are discharged from the conduit,

and second means located between said first means and said conduit means for admitting only a selected number of the blades from said first means into said conduit means, said second means acting to intermittently admit the blades 5 into said conduit means, said second means comprising a plate mounted for oscillation on a longitudinal axis thereof, said plate being formed with an aperture adapted to substantially register with said conduit means in one position of said 10 plate so as to permit a predetermined number of yucca blades to pass from said first means into said conduit means, said plate being arranged to occupy another position at another time wherein said aperture is out of registry with said 15 conduit means whereby yucca blades in said first means are positively prevented from passing from said first means into said conduit means.

7. A machine for longitudinally splitting yucca blades, said machine comprising a hopper including individual declining chutes, a battery of declining guide tubes having their receiving ends aligned with the lower ends of said chutes, a battery of rotary knives adjacent the lower ends 20 of said guide tubes, an oscillating plate supported on a longitudinal axis thereof and interposed between the lower ends of said chutes and the upper ends of said guide tubes, said plate being formed with individual apertures, said apertures being arranged to register with the corresponding 25 chutes and guide tubes in one position thereof so as to permit a predetermined number of yucca blades to discharge from each chute into the corresponding guide tube, said apertures in another 30 position of said plate being out of registry with the corresponding chutes and guide tubes so as to prevent any yucca blades from passing from the chutes into the guide tubes, said guide tubes being arranged to guide the yucca blades into engagement with the rotary knives. 40

8. A machine for longitudinally splitting yucca blades, said machine comprising a hopper including individual declining chutes, a battery of declining guide tubes having their receiving ends aligned with the lower ends of said chutes, a battery of rotary knives adjacent the lower ends 45 of said guide tubes, an oscillating plate supported on a longitudinal axis thereof and interposed between the lower ends of said chutes and the upper ends of said guide tubes, said plate being formed with individual apertures, said apertures being arranged to register with the corresponding chutes and guide tubes in one position thereof so as to permit a predetermined number of yucca blades to discharge from each chute into 50 the corresponding guide tube, said apertures in another position of said plate being out of registry with the corresponding chutes and guide tubes so as to prevent any yucca blades from passing from the chutes into the guide tubes, said 55 guide tubes being arranged to guide the yucca blades into engagement with the rotary knives, and opposed rollers supported intermediate said oscillating plate and the upper ends of said guide tubes and acting to forcibly position the yucca 60 blades in the guide tubes and into engagement with said rotary knives. 65

9. A machine for longitudinally splitting yucca blades, said machine comprising a hopper including individual declining chutes, a battery of declining guide tubes having their receiving ends aligned with the lower ends of said chutes, a battery of rotary knives adjacent the lower ends 70 of said guide tubes, an oscillating plate supported on a longitudinal axis thereof and interposed be- 75

tween the lower ends of said chutes and the upper ends of said guide tubes, said plate being formed with individual apertures, said apertures being arranged to register with the corresponding chutes and guide tubes in one position thereof so as to permit a predetermined number of yucca blades to discharge from each chute into the corresponding guide tube, said apertures in another position of said plate being out of registry with the corresponding chutes and guide tubes so as to prevent any yucca blades from passing from the chutes into the guide tubes, said guide tubes being arranged to guide the yucca blades into engagement with the rotary knives, and adjustable yucca blade supporting fingers arranged along said rotary knives for supporting the yucca blades relative to said rotary knives as the yucca blades issue from said guide tubes.

10. A machine for longitudinally splitting yucca blades, said machine comprising first means for holding and feeding the yucca blades, conduit means into which the blades are selectively fed from said first means, rotary cutters adjacent the conduit means for longitudinally splitting the blades as they are discharged from the conduit, and second means located between said first means and said conduit means for admitting only a selected number of the blades from 10 said first means into said conduit means, said rotary cutter comprising a rotary shaft having a squared portion intermediate its ends, cutter disks having squared openings disposed on said squared portion, spacers between the disks, said shaft 15 having threaded portions containing nuts clamping said disks and spacers together on said shaft.

ORLIE A. HAWKINS.
